MASSACHUSETTS.

PICKING AND FILLING MATTRESS MACHINE.

Application filed April 20, 1925. Serial No. 24,434.

In filling mattresses the material, of whatever character it is, must be free from dust and it must also be shredded so that it will not be fed into the mattress in lumpy condition. Various machines have been devised for this purpose but for various reasons none of them has proved entirely satisfactory. The machine, however, which we have devised we believe to be a great practical improvement on those which have heretofore been constructed in that it is capable of thoroughly separating the filling material, allowing all heavier particles of dirt to drop from it and also enabling the filling material to be passed through the machine as many times as is desirable and finally filling the mattress by blowing the filling into it.

Our invention will be understood by reference to the drawings in which it is shown in its preferred form.

Fig. 1 is a side elevation of the machine.

Fig. 2 is a vertical section somewhat enlarged.

Fig. 3 is a horizontal section showing the movable parts, and Fig. 4 shows a means whereby a mattress may be coupled to the air duct.

1 is a stand on which the apparatus is mounted. 2 is the floor of the apparatus on which is mounted brackets 3 on which the main casing 4 of the machine is mounted. This casing comprises a perforated false bottom plate 5 and for its top has a part 6 which preferably as shown slopes inwardly and upwardly and ends in a pipe 7 at its top. 8 is a rotary shaft which passes up through the floor 2 and plate 5. It is held in place by collars 9 in a usual way, 10 representing a ball-bearing mechanism of ordinary construction which rests against the under surface of the perforated plate 5. On this shaft and above the plate 5 is a ball-bearing collar 11 on which rests the plate 12 having thereon another collar 13 between which and the collar 11 the plate 12 is clamped so that the rotation of the shaft 8 will carry with it the plate 12. This shaft 8 is set in a socket 14 in the bottom of a casing 15 mounted on the stand 16. On the shaft 8 is mounted a bevelled gear 17 to which rotation is given by a second bevelled gear 18 mounted on shaft 19 and operated by means of belt 20 running over a pulley

on the shaft 19 and a second pulley on the 55 shaft 21 of the motor 22.

On the plate 12 are mounted four arms 23 each carrying a series of fingers 24 and above them other fingers 25 are mounted in staggered relation thereto, these last fingers 60 25 being mounted upon a spider frame 26, the arms of which are carried by a plate 27 and collar 28 in which the shaft 8 turns. 29 is an oil cup to lubricate the shaft. The outer ends of the spider frame 26 are attached to the interior surface of the casing 4 at 30.

From the above it will be understood that while the spider carrying the fingers 25 is stationary, the spider 23, carrying the fingers 70 24, is rotary and as the fingers of the rotary spider are quite close to the fingers on the stationary spider any material fed into the chamber containing the spiders will be torn and shredded to a considerable extent and the 75 opportunity will be offered for all the dirt and heavy foreign matter to drop out therefrom. This matter will fall down through the perforations in the plate 5 onto the flooring 2 and may be removed therefrom 80 through the door 31.

32 is a blower fan of ordinary construction which is operated from a motor 33. The interior of this fan is connected with the chamber within the casing 4 by a pipe 85 34 and the fan is rotated to cause the air and material which has been drawn into it to be forced out through the pipe 35 in the direction of the arrow. The pipe 35 connects with a three-way coupling 36 the lower edge of which has an opening connecting with the pipe 7 while the third opening is connected with a pipe 37 which leads to the mattress. The opening between the coupling 36 and the pipe 37 is controlled by a 90 damper 38 which may be operated in any usual way from the outside.

39 is a hopper into which the filling material is fed by hand. It will be noted that this hopper has at the bottom perforations 100 40 and that the casing 4 is perforated as at 41. The casing also has a shelf 42 to which is pivoted a damper 43 capable of resting in either one of two positions as shown in Fig. 2 where the damper 43 is in 105 filling position, that is to say, the machine is in condition to be filled through the mouth of the hopper the filling material

striking the damper 43 and sliding down towards the casing. When the casing has had a sufficient load of filling the damper 43 is turned up into the position shown in 5 dotted lines so that no more filling can be put into it.

As shown in Fig. 2 the apparatus is in position to be filled. It is understood that at this time the blower 32 is active to withdraw 10 air from the casing this air being furnished through the perforations 40 and 41 in the lower part of the hopper. At this time also as shown in Fig. 2 the damper 38 is closed so that there is a circulation from the casing 15 through the pipe 34, fan 32, pipe 25 and collar 7 back into the casing. The motor 22 is started and the spider 23 is rotated so that the material as it is fed into the casing is torn by the cooperation of the 20 moving fingers 24 and the stationary fingers 25.

When the casing is sufficiently full the damper 43 is closed into its dotted position and the filling is drawn out through the 25 pipe 34 and back through the pipes 35 and 36 and pipe 7 and thus circulated until such time as it is considered that the material has been properly treated. To inspect the 30 condition of the material a door 44 which may be of glass is provided in the upper part of the casing. Experience shows when the proper amount of tearing or shredding has been given to the material. When the 35 process is finished the damper 38 is thrown down as shown in dotted lines in Fig. 2 thus substantially closing the passage to the pipe 7 and opening the passage to the pipe 37. The fan 32 continuing its operation draws the material out of the casing and delivers it into the pipe 35 through which and the coupling 36 it is delivered to the pipe 37 and from it passes to the mattress.

To attach the mattress to the pipe we have preferred to use a clamp such as is 45 shown in Fig. 4 (see also Fig. 1) where 46 is a bracket to which is pivoted two segments 47 and 48. The free ends of these semi-annular pieces have lugs 49 and 50. The lug 49 has pivoted thereto an arm 51 threaded at its free end and setting into a slot end of the lug 50. 52 is a sleeve which is on the arm 51 and 53 is a winged nut on the arm 51 by which the ends of the segments 47 and 48 may be drawn towards the lug 49. A slit in the mattress is placed over the 55 end of the pipe 37 in the usual way and the clamp 47, 48 is passed around it as shown in Fig. 1 and the lugs 49 and 50 are then clamped together as closely as possible by 60 means of the winged nut 53. 54 is a handle on the end of the screw 51. As shown in Fig. 1 the end of the pipe 37 is spread or formed into a collar as at 371 to assist in 65 making a good, air-tight joint at this point.

It will be readily seen that the details

of the construction of this machine may be otherwise than as shown and described above. We believe, however, that in its present form our invention is embodied in a construction which is simple to manufacture and is capable of very satisfactory use.

What we claim as our invention is:—

1. In a machine of the kind described, a rotary member mounted on a vertical shaft 75 and a stationary member, each member having fingers, the fingers on the rotary member being arranged in staggered relation to the fingers on the stationary member, a casing containing said members, and having a delivery opening for said material and a separate delivery means for the dust falling therefrom, and means for causing the material to be shredded to pass between said fingers whereby said fingers will tear and 80 separate said material and cause it to deliver dust and dirt to said delivery means and allow said material to be drawn off through said delivery opening.

2. In a machine of the kind described, a 90 rotary member mounted on a vertical shaft and a stationary member, each member having fingers, the fingers on the rotary member being arranged in staggered relation to the fingers on the stationary member, a casing containing said members, and means for causing the material to be shredded to pass between said fingers, and means comprising 95 a fan and an opening in said casing and connections between said fan and said opening whereby said fan will draw such material from said casing and a separate delivery means adapted to allow the separate collection of the dust and dirt falling from 100 said material.

3. In a machine of the kind described, a 105 rotary member mounted on a vertical shaft and a stationary member, each member having fingers, the fingers on the rotary member being arranged in staggered relation to the fingers on the stationary member, a casing containing said members, and means for causing the material to be shredded to pass between said fingers, and means comprising 110 a fan and an opening in said casing and connections between said fan and said opening whereby said fan will draw such material from said casing and transfer it to a place of delivery, and a separate delivery means adapted to allow the separate collection of the dirt and dust falling from 115 said material while in process.

4. A machine of the kind described 120 comprising a casing having mounted there-in a stationary member mounted on a vertical shaft and a rotary member, each member having fingers, the fingers on the rotary member being arranged in staggered relation to the fingers on the stationary member, said casing having a perforated 125 false 130

bottom forming a chamber below it to receive dust, said chamber having a clean-out door.

5. A machine of the kind described comprising a casing having mounted therein means for shredding material fed thereto, an inlet hopper on one side thereof, a delivery opening at the other side, an exhaust fan and connections with said delivery opening,

said hopper being perforated at its bottom, ¹⁰ and said casing having perforations in its wall adjacent said hopper and a damper located to shut off the lower part of said hopper when in one position and to close the entrance to said casing when in its other ¹⁵ position.

GUSTAF T. GUSTAFSON,
ERIK M. SCHWARTZ.
